UNITED STATES PATENT OFFICE.

WILLIAM W. WILDER, JR., OF CINCINNATI, OHIO.

OFFICE-INDICATOR.

SPECIFICATION forming part of Letters Patent No. 697,907, dated April 15, 1902.

Application filed July 29, 1901. Serial No. 70,039. (No model.)

To all whom it may concern:

Be it known that I, WILLIAM W. WILDER, Jr., a citizen of the United States of America, and a resident of Cincinnati, in the county of 5 Hamilton and State of Ohio, have invented certain new and useful Improvements in Office-Indicators, of which the following is a specification.

The object of my invention is an indicator 10 to be placed upon the doors of offices which will indicate at a glance to an observer several points of information concerning the movements of the proprietor—as, for instance, his whereabouts and if he be out of the office 15 the day and the hour of his return—which may be operated to indicate this data by a single key, and which is simple in construction and ornamental in appearance. This object is attained by the means described in the annexed 20 specification and illustrated in the accompanying drawings, in which—

Figure 1 is a front elevation of an indicator embodying my invention. Fig. 2 is a similar view with the front plate removed. Fig. 3 is a 25 sectional view, upon an enlarged scale, taken through line $\alpha\alpha$, Fig. 2, the ends of the base-plate being broken off. Fig. 4 is a detail sectional view, upon a still more enlarged scale, showing the key and the disks revolved there- 30 by. Fig. 5 is a detail plan view of one of the bracket-arms secured to the base-plate for guiding the disks. Fig. 6 is a sectional view of the same. Fig. 7 is a side elevation of the key. Fig. 8 is an inverted plan view of the 35 same.

Referring to the parts, secured to base-plate A are four radial arms B, of one pattern and set at equal distance from a central post a, which is secured to the base-plate. Arms 40 B have formed integral with them three inwardly-projecting flanges b, b', and b'', respectively, parallel to the base-plate, flange b being at the greatest distance from post a and resting against the base-plate, flange b'' 45 being at the shortest distance from the post and at the greatest distance from the base-plate, and flange b' being midway between flanges b and b'' both as to its distance from post a and from the base-plate. Upon the outermost face of each arm B is a recess b³. Upon flanges b rests a circular disk C, above which

on flanges b' rests a second circular disk D, of a smaller diameter. Above disk D upon flanges b'' rests a third circular disk E, of a diameter smaller than that of disk D. In the 55 way formed by recesses b³ rests a fourth disk F, in the shape of a circle of a diameter substantially equal to disk C, but with a segment f cut out of it to expose the edges of disks C, D, and E. Disks C, D, E, and F are concentric, each having a central perforation in it to pass over post a, the edges of said perforations being notched, so that the notches may be engaged by teeth gg' of a key G, which fits down over post a. 60

Disk C has numerals in regular order indicating the hours and half-hours marked upon its edge. Similarly, disk D upon its edge has numerals indicative of the day of the month. Disk E has the months marked upon its edge. 70 Disk F has printed radially upon its face the words "Out of city," upon the left of that at ninety degrees the word "Will," and at ninety degrees on the right the word "Return." Midway between this sign and arranged similarly thereto are the words "In office," "Walk in," as shown in dotted lines, Fig. 1. 75

Through the four corners of face-plate H screws are passed inward to plate A, the inner face of plate H bearing against the outermost face of arms B and, together with recesses b³, forming a way for disk F. In it are four radial openings h, h', h'', and h''' at ninety degrees apart. Through opening h the words "Out of city," "In office," and through openings h and h'' the words "Will return" and "Walk in" may be alternately exposed by the rotation of disk F. Opening h''' is large at each end, the inner enlarged portion coming over the edge of disk E to expose the names 85 of the months, the central reduced portion over disk D to expose the numerals indicating the day of the month, and the outer enlarged portion coming over the edge of disk C to expose the numeral indicating the hour. Plate 90 H has a central perforation h⁵ for the passage of key G. Above the disks plate A has an opening h⁴, through which the name of the proprietor may be seen. 95

Post a has five annular beads formed upon it at distances apart equal to the distances between the disks. Key G has a hollow shank 100

g^2 to fit over post a , and upon one side is cut a spring-arm g^3 , which has a small inwardly-projecting tooth g^4 , which springs into the grooves between the beads upon post a , so that when tooth g^4 is in the groove between the uppermost bead and the one next to it teeth g^4 engage the notches in disk F, and when in the successively lower grooves engages successively disks E, D, and C. When tooth g^4 is in the lowest groove, teeth g^4 are below disk C, so that if the key be then turned the position of none of the disks is affected thereby. This position is the one the key is to be left in after the indicator has been set.

In use the indicator being attached to the door of an office to indicate that the proprietor is out of the city and that he will return, he brings the key to its uppermost position, and by turning it rotates disk F to the position shown in Fig. 1. Then he pushes the key inward to the next groove, spring-arm g^3 allowing it to move inward and snapping tooth g^4 into the next groove. By rotation of the key he then turns disk E to expose the name of the month of his return. Similarly he arranges disks D and C to indicate the date and hour of the same, and then pushes the key to its innermost position, so that should it then be turned it would not affect the position of the disks, and a person unfamiliar with the workings of the device could not tamper with it.

What I claim is—

1. In an office-indicator the combination of a base-plate, a forwardly-projecting post thereon, a face-plate having slots therein secured to the base-plate, concentric sign-bearing disks mounted between the base and face plate and being perforated to pass the post, a key to pass over said post and means for holding it at points upon the post opposite to the respective disks to engage them to expose

various data at the slots in the face-plate, substantially as shown and described.

2. In an office-indicator the combination of a base-plate, a face-plate having slots cut therein, a series of circular concentric disks mounted rotatably between said plates the disks decreasing in diameter from the base-plate outward with the exception of the outermost which has a segment cut out to expose the other disks said outermost disk bearing signs upon its face and the others upon their edges, and means for rotating the disks to expose the signs at the slots of the face-plate, substantially as shown and described.

3. In an office-indicator the combination of a base-plate, radial arms secured thereto about a common center each having a similar series of parallel inwardly-projecting flanges at increasing distances from the base-plate and decreasing distances from the center forming circular ways, sign-bearing disks seated in the ways formed by the similar flanges, a slotted face-plate and means for rotating the disks to expose the signs at the slots, substantially as shown and described.

4. In an office-indicator the combination of a slotted face-plate, a base-plate, a stud bearing a series of annular beads secured to the base-plate, a series of disks between the base and face plate having notched perforations to pass the post and situated at distances apart equal to the distances apart of the annular beads, and a key having a hollow shank to fit over the post a spring-finger to engage the post between the beads and teeth to engage the notches in the disks to rotate them to expose different signs at the slots, substantially as shown and described.
